UNITED STATES PATENT OFFICE.

JOSEPH S. BEEMAN, OF LONDON, ENGLAND.

SUPPORT FOR FILAMENTS OF INCANDESCENT LAMPS.

SPECIFICATION forming part of Letters Patent No. 291,464, dated January 1, 1884.

Application filed April 23, 1883. (No model.) Patented in England July 11, 1882, No. 3,279, and in France January 9, 1883.

To all whom it may concern:

Be it known that I, JOSEPH SAMUEL BEEMAN, of 67 Strand, London, England, have invented a new and useful Improvement in Electric 5 Lamps, (for which I have obtained patent in Great Britain, dated July 11, 1882, No. 3,279, and in France January 9, 1883,) of which the following is a specification.

My invention has for its object to prevent or 10 arrest injurious movement or vibrations of the carbon filament or filaments of incandescent electric lamps, and to prevent the filament being broken or injured by sudden shocks. In order to effect these objects, a projection or 15 pendent piece is fitted to or formed on the interior of the bulb or globe of the lamp, so as to embrace and support, but at the same time be out of contact with, the filament or filaments, when in its or their normal position.

20 The annexed drawings illustrate a method of carrying out my invention, Figures 1 and 2 being vertical sections, at right angles to each other, of an incandescent electric lamp provided with a supporting device according to 25 my invention.

A is the bulb of the lamp; B, the carbon filament; C, the conducting-wires, and D the supporting device. It is preferred to make this supporting device of platinum; but it 30 may be made of glass, porcelain, mica, or other suitable material, and may be fused in, otherwise attached to, or formed in one with, the globe A during its manufacture. The pro-

jecting portion d of the supporting device D is forked, or is in the form of a saddle or crutch, as shown in Fig. 2; or it may be of any other suitable shape, to embrace both sides of the upper or curved portion of the filament or filaments, which filament or filaments should be arranged between the limbs or prongs of the supporting device, but without being in contact therewith when the said filament or filaments is or are in the normal position. Should the lamp, however, be subjected to a sudden shock or vibration, the filament or filaments will be brought into contact with one or other of the prongs or depending pieces of the supporting device, which would thus prevent the filament or filaments from being broken or injured by the vibrations of the 50 lamps.

I claim as my invention—

In incandescent lamps, the combination, with the globe or bulb and the incandescent filament, of a projection or pendent piece fitted to or 55 formed on the interior of the globe in a position to embrace and support the filament when the latter is inserted in place in the globe, as hereinbefore set forth.

In testimony whereof I have signed this 60 specification in the presence of two subscribing witnesses.

J. S. BEEMAN.
